UNITED STATES PATENT OFFICE.

WALTER H. PRUEFER, OF PROVIDENCE, RHODE ISLAND, ASSIGNOR TO THE FIRM OF FISCHER AND PRUEFER, COMPRISING SIGMUND FISCHER AND WALTER H. PRUEFER, BOTH OF PROVIDENCE, RHODE ISLAND, COPARTNERS.

PROCESS OF FORMING BUTTON-SHANKS.

1,087,550.

Specification of Letters Patent. Patented Feb. 17, 1914.

Application filed April 18, 1913. Serial No. 761,967.

To all whom it may concern:

Be it known that I, WALTER H. PRUEFER, a citizen of the United States, and resident of the city of Providence, in the county of Providence and State of Rhode Island, have invented certain new and useful Improvements in Processes of Forming Button-Shanks, of which the following is a specification.

This invention relates to a new process of forming a button shank, and consists in drawing a piece of sheet stock up into a cup-shape and forming a flange around the open edge of the cup, then reducing that portion between the flange and the closed end forming a reduced neck portion and a head on the latter end, then flattening said head and piercing said flattened portion to form an eye, turning the edges of the pierced stock from both sides of the eye inward until they practically meet then shaping the base portion to be readily attached to the button head.

A further object of the invention is to turn the edges of the base outward forming a flaring cup-shaped flange adapted to be spread to engage an undercut recess in the underside of the button head whereby the shank is completely formed and attached in position without the use of solder.

With these and other objects in view, the invention consists of certain novel features of construction, as will be more fully described and particularly pointed out in the appended claims.

Of the accompanying drawings: Figure 1—is a side elevation showing a button head in cross section and a finished shank formed by my improved process connected to said button. Fig. 2—is a sectional elevation illustrating the result of the first step in the process, which is that of drawing a piece of sheet metal up into a cup-form leaving a flange around its open edge. Fig. 3—is a sectional view representing that portion between the flange and the closed end as having been reduced to form a neck portion and a head. Fig. 4—is a plan view showing the spherical-shaped head after reducing the neck portion. Fig. 5—is a side elevation illustrating the head portion as having been flattened. Fig. 6—illustrates the flattened portion as having been pierced. Fig. 7—shows the pierced edges of the stock as

rolled or turned inward, the opposite edges 55 of the stock meeting all around the internal diameter of the eye. Fig. 8—illustrates the flange portion as having been turned outward forming a flaring cup-shape to be inserted into the button, as illustrated in 60 Fig. 1. Fig. 9—is a plan view of the finished shank showing the flattened head and the engaging flange.

The usual button shank has been heretofore constructed of a piece of wire bent into 65 a loop form, and the ends of the wire soldered to a cup, which cup is connected to the back portion of the button head. But in my improved construction it will be seen that the wire ends are necessarily attached 70 to the cup portion by solder, the heat of which is very objectionable as it destroys the plating and forms a rough and unfinished article.

The object of my improved invention is 75 to provide a shank having a fastening flange all constructed of a single integral piece of metal the construction of the shank and fastening of the shank to the button being entirely completed without the use of solder 80 by which construction an extremely strong and durable button shank is provided, the same being very neat and attractive in appearance with no joints exposed.

In carrying out my improved process I 85 first draw a piece of flat stock up into a deep cup-shape 10, as illustrated in Fig. 2, leaving a flange 11 around its open edge. The stock between the flange and the closed end 12 is reduced by swaging or otherwise, 90 as at 13, forming a reduced neck portion and leaving the outer end 12 in a substantially spherical form thereby providing a head. This head 12 is then flattened as into the form illustrated at 14 in Figs. 5 and 9, 95 and this flattened portion is then pierced, the center portion being removed forming an eye 15. One of the features of the invention is that the edges 16 of the pierced portion of the stock are rolled or turned in- 100 ward toward each other, as illustrated in Fig. 7, forming substantially a complete circle in cross section of the stock around the eye, said edges meeting substantially in a medial line. The base flange 11 may be 105 then shaped into any suitable form whereby it may be readily attached to the button head 18, but I preferably turn the edges of

this base portion outward, as at 19, see Fig. 8, forming a flaring or beveled cup-shaped flange which is particularly adapted to be inserted into an undercut recess, such as 5 that illustrated at 17, in Fig. 1, in the back of the button 18, whereby this flange may be spread and adapted to fill the recess and engage these undercut walls for the purpose of firmly attaching the shank to said head.

10 It will be observed that by my improved process I form the shank complete without the use of solder, and also attach the shank thus formed to the button head without the application of any heat thereto. A further 15 advantage in my present invention is that the shank may be formed of rolled plate and by drawing the same up into a cup form, flattening and piercing the head and then turning the edges of the pierced stock 20 inward toward each other it will be noted that only the precious metal surface is exposed, the base metal lining being completely covered.

I claim:

25 1. The process of making hollow button shanks consisting in drawing sheet stock up into cup shape and forming an attaching flange at the open edge, shaping the closed

end into a substantially spherical head, flattening said head, piercing said flattened 30 head to form an eye, and turning the opposite edges of the pierced portion inward until they meet and abut in substantially a medial line whereby only the outer surface of the stock forming said eye is exposed. 35

2. The process of making hollow button shanks consisting in drawing sheet stock up into cup shape and forming an attaching flange at the open edge, reducing the diameter of the cup between the ends to form an 40 elongated reduced shank and simultaneously shaping the closed end into a substantially spherical head, flattening said head, piercing said flattened head to form an eye, and turning the opposite edges of the pierced 45 portion inward until they meet and abut in substantially a medial line whereby only the outer surface of the stock forming said eye is exposed.

In testimony whereof I affix my signature 50 in presence of two witnesses.

WALTER H. PRUEFER.
